Attorney

UNITED STATES PATENT OFFICE.

EMIL SCHREIER, OF VERDIGRE, NEBRASKA, ASSIGNOR TO EMIL PAUL SCHREIER.

STOCK-TANK.

1,272,720.

Specification of Letters Patent. Patented July 16, 1918.

Application filed January 18, 1917. Serial No. 143,092.

To all whom it may concern:

Be it known that I, EMIL SCHREIER, a citizen of the United States, residing at Verdigre, in the county of Knox and State of Nebraska, have invented certain new and useful Improvements in Stock-Tanks, of which the following is a specification.

The present invention relates to improvements in stock tanks.

10 The primary object of the invention is the provision of a stock tank which embodies a plurality of staves arranged for co-operation whereby they will form a substantial and water tight structure.

15 Another object of the invention is the provision of a tank such as above referred to, which comprises a plurality of removable staves having interlocking engagement with each other whereby they will be held in 20 normal positions against any undesired displacement.

Still another object of the invention is the provision in a stock tank of a plurality of staves having longitudinal grooves formed 25 in their contacting edges and designed to receive suitable keys whereby the staves will be held in co-operative relation forming a substantial structure.

30 A further object of the invention is the provision of a stock tank including a plurality of interlocked staves having the upper ends thereof rounded for preventing the accumulation of food or other undesired substances which would tend to cause 35 diseases among the animals which are fed from the same.

35 A further object of the invention is the provision of a stock tank including a plurality of staves which when arranged in 40 proper relative position form a tank of circular or any other desired contour, together with means for anchoring the same upon a suitable base.

45 A still further object of the invention is the provision of a stock tank such as above described, which will be comparatively simple and inexpensive to manufacture, reliable and efficient in use, and readily operated.

50 With the above and other objects in view, the present invention resides in the novel features of construction, formations, combinations, and arrangements of parts to be hereinafter more particularly described, claimed, and illustrated in the accompanying drawing forming a part of the present 55 application and in which:

Figure 1 is a side elevation of a stock tank constructed in accordance with the present invention, with a portion thereof broken away and showing one of the keys in cross section;

Fig. 2 is a top plan view of a circular tank constructed in accordance with the present invention;

Fig. 3 is a detail perspective view of one of the staves; and

Fig. 4 is a detail transverse sectional view taken through a portion of a tank and showing means for mounting the same upon a suitable base and locking the same thereon.

Fig. 5 is an end view of a modified form of one of the staves. Fig. 6 is a plan view of a portion of the stave shown in Fig. 5.

Referring now to the accompanying drawing by corresponding characters of reference throughout the several views, the numeral 5 designates in general a stock tank or other suitable structure formed in accordance with the present invention. The same can be of any shape and size but is 75 preferably of a circular formation and comprises a plurality of segmental shaped staves 6 which contact at their opposite and adjacent edges forming a water tight structure.

85 The vertical side edges of the staves 6 are provided with confronting grooves 7 of corresponding shape and size forming when the staves are in normal position as disclosed in Fig. 2, vertical passages, into which can 90 be poured suitable fillers 8 which constitute when hardened keys which securely lock the staves against any undesired relative movement or displacement.

95 As clearly shown in the various figures of the drawing, the upper end of the staves 6 and adjacent portions of the keys or fillers 8 are rounded as shown at 9, which prevents the accumulation thereon of food or other foreign substances which would have a tendency to cause diseases among the animals to be fed from said tank.

100 As shown in Figs. 1 and 2 of the drawing the tank is mounted preferably upon a flat portion of ground, but as shown in Fig. 4 thereof the tank is mounted upon a base 10 of any preferred shape and constructed from any suitable material.

105 This base 10 is provided with recesses 11 at intervals around its edges which correspond to the vertical passages between said staves and when the filler 8 is poured be-

tween the adjacent edges of the staves and through the said passages, the same enters the recesses 11 forming a locking means which firmly secures the tank upon the base 10.

From the foregoing description taken in connection with the accompanying drawing, it will be manifest that a stock tank is provided which will fulfil all of the necessary requirements of such a device, and while the staves 6 are preferably constructed from cement or other plastic material, it is to be understood that I am not to be limited to the use of such material only but may construct the same from any other substance which will answer the necessary purposes. It should be further understood in this connection that various minor changes in the specific details of construction can be resorted to within the scope of the appended claims, without departing from the spirit or sacrificing any of the advantages of the invention.

In order to prevent the breaking of the ribs formed by the grooves 7, a series of triangular reinforcing ribs 12 are provided as shown in Figs. 5 and 6, thus strengthening the most fragile portion of each stave and also forming means for securely binding the cement filler within the groove.

Copies of this patent may be obtained for five cents each, by addressing the "Commissioner of Patents, Washington, D. C."

Having thus fully described the invention what is claimed is:

1. A stock tank of the character described comprising a multiplicity of arcuate staves having opposed grooves in their adjacent vertical edges, a base having recesses therein, in registration with the grooves in the staves, and fillers engaging said opposed grooves and extending below the lower ends of the staves and also engaging the recesses on the base which are in registration with the opposed grooves in which they are engaged; substantially as and for the purpose set forth.

2. A stock tank of the character described comprising a plurality of staves having grooves formed in the adjacent edges thereof, triangular reinforcements disposed within the said grooves and disposed in a plane at right angles to the length of the grooves and connecting the sides of the grooves with the bottoms thereof, and fillers occupying said grooves and contacting with said reinforcements.

In testimony whereof I affix my signature in the presence of two witnesses:

EMIL SCHREIER.

Witnesses:

W. C. BRONSON,
T. A. TIKALSKY.
